(57) **CLAIM**

The ornamental design for a shoe outsole, as shown and described.

DESCRIPTION

FIG. 1 is a front perspective view of a shoe outsole showing our new design;

FIG. 2 is a bottom view thereof; and,

FIG. 3 is a rear perspective view thereof.

The photographic area is claimed. The lack of a broken or solid line immediately adjacent to the photographic area indicates a claimed edge of the design. The broken lines showing the remainder of the shoe are for environmental purposes only and form no part of the claimed design.
